United States Patent

Des. 241,960
Patented Oct. 19, 1976

241,960

SIMULATIVE TOY VEHICLE

Donald Huffman, Westmount, Montreal, Canada, assignor
to Coleco Industries, Inc., Hartford, Conn.

Filed Sept. 20, 1974, Ser. No. 507,773

Term of patent 14 years

Int. Cl. D21—01

U.S. Cl. D34—15 AJ

FIG. 1

FIG. 2

FIG. 3

FIG. 4

FIG. 5

FIG. 1 is a side elevational view of a simulative toy vehicle showing my new design, the opposite side being a mirror image thereof;

FIG. 2 is a top plan view thereof;

FIG. 3 is a bottom plan view thereof;

FIG. 4 is a front elevational view thereof; and

FIG. 5 is a rear elevational view thereof.

I claim:

An ornamental design for a simulative toy vehicle, as shown and described.
